UNITED STATES PATENT OFFICE.

FREDERICK L. GOSS AND SAM G. GOSS, OF CHICAGO, ILLINOIS, ASSIGNEES
TO THE GOSS PRINTING PRESS COMPANY, OF SAME PLACE.

INK-ROLLER ADJUSTMENT FOR PRINTING-MACHINES.

SPECIFICATION forming part of Letters Patent No. 363,327, dated May 17, 1887.

Application filed October 11, 1886. Serial No. 215,925. (No model.)

To all whom it may concern:

Be it known that we, FREDERICK L. Goss and SAM G. Goss, citizens of the United States, residing at Chicago, in the County of Cook and State of Illinois, have invented a certain new and useful Improvement in Ink-Roller Adjustments for Printing-Machines, and we hereby declare the following to be a full, clear, and exact description of the same.

Our improvement has for its object the provision of means whereby the various ink-rollers may be readily adjusted singly to bear with greater or less pressure upon their adjacent cylinders, and to enable them all to be thrown off simultaneously from contact with the cylinders when the press is not running, to avoid the flattening effect upon them of their contact with the cylinders when stationary, this last-named object being desirable, owing to the fact that the composition of which the ink-rollers are formed, being soft, if allowed to rest for a sufficient length of time against an object without rotating they become flattened by the pressure upon the bearing-surfaces, and are thus destroyed.

In the drawings, Figure 1 shows in end elevation, partly sectional, taken on the line 1 of Fig. 2 and viewed in the direction of the arrow, our improved throw-off and adjusting mechanism for the ink-rollers applied transversely to the printing-press frame, the rollers being represented by dotted lines, in contact with the form-cylinder of a cylinder-press and with the vibrator or ink-drum, the latter and the form-cylinder being represented by dotted lines. Fig. 2 is a broken sectional view taken on the line 2 of Fig. 1, and viewed in the direction of the arrow; Fig. 3, a similar view taken on the line 3 of Fig. 2, and viewed in the direction of the arrows; Fig. 4, a similar view taken on the line 4 of Fig. 2, and viewed in the direction of the arrow; and Fig. 5, a similar view taken in the line 5 of Fig. 2, and viewed in the direction of the arrow.

A denotes the supporting-frame for the mechanism, and forms part of the frame of the printing-press, which, however, is not shown in the drawings more than is required to indicate its position and that of the form-cylin-

der and ink-rollers with reference to each other, since it forms no part of our present improvement.

B is a skeleton frame, comprising two vertical standards and a top cross-piece and bolted to the frame A and supporting the various ink-rollers, the mechanisms hereinafter described for adjusting them independently of each other and for throwing them off simultaneously, and the vibrator or ink-drum which receives the ink applied in the usual manner.

C is this ink-drum or vibrator, journaled at opposite ends in the frame B and rotating near the form-cylinder D of the press. Inside the frames B are blocks n, having backward-extending flanges n', by which they are bolted on the top of the frame A, and into the face of each is dovetailed, as shown in Fig. 3, a flaring block or bearing, E, having a semicircular extension, r, on its lower edge, a semi-cylindrical projection, q, on its inner face, and recessed centrally toward its upper edge to produce extensions p and p', each extension p and p' being also provided on its outer edge with an ear, o, having a threaded opening containing a screw-pin, o', provided with a wing-nut, o'', for a purpose hereinafter described.

Below each block E is a cam, F, in contact with the semicircular projection r on the block, and supported to be oscillated upon a rock-shaft, F', between the frames A and blocks n, and provided at one projecting extremity with a hand-lever, F'', Fig. 2. Thus by rocking the shaft F' the cams F, under the blocks E at opposite ends of the frame B, raise and lower the blocks as desired, and support them in their adjusted positions.

From the nature of the views selected to illustrate our improvement, only one side of the apparatus is shown. It will be understood, however, that the adjusting mechanism hereinbefore and hereinafter described is also provided at opposite ends of the ink-rollers. Thus, of the parts already described, the frame B, flanged block n, reciprocating bearing E, and semi-cylindrical extension q are duplicated on the side not shown. On the inner side of each block E, on their flat sides,

extending, respectively, along the parts p and p' , are semi-cylindrical boxes G and G' , provided with extensions m from their flat sides, at which the boxes are pivoted at their lower 5 extremities to the blocks E , and at their outer edges they carry, respectively the extensions l and l' , provided with curved slots x to receive the pins o' in the projections o on the blocks E , whereby the boxes G G' may be 10 swung to any desired position and fastened therein by means of the wing-nuts o^2 .

Within the boxes G and G' and the box g , which is stationary, are screws H , extending through jam-nuts k and k' at opposite ends 15 of the boxes, and carrying at their upper extremities the bearings I , preferably of the form shown, for the ink-rollers, which are held therein at their journal ends by suitable cotter-pins, y . The screw H in each box may 20 be moved longitudinally by proper manipulation of the jam-nuts to adjust the bearing carried by it for the purpose of adjusting the respective ink-roller at its opposite ends, and a transverse screw, H' , for each box, firmly 25 holds the screw H in its adjusted position. It will thus be seen that the extreme ink-rollers, K and K' , may be adjusted with reference to the cylinder D and vibrator C , independently of each other, to bear with greater or less 30 pressure by the swinging motion of which they admit; that these same rollers and the central one, K^2 , in the stationary box g , may be independently adjusted at either end by manipulating the screw H to "true" them 35 with reference to the cylinder D and vibrator, and that the three rollers may simultaneously be moved into and out of contact with the cylinder D and vibrator by rocking the shaft F .

On the upper side of each frame B is an adjustable supporting device for the journal end 40 of an ink-roller, K^3 , between the cylinder D and vibrator C . It comprises a bracket, L , bolted to the top of the frame B , and carrying, if desired, at its extremity an auxiliary bearing, I' , for the journal end of the roller K^3 , like the bearings I , but stationary, and merely serving the purpose of a rest for the roller K^3 when not required to be used, in which to place it in a convenient position for future use 45 when removed from its position shown by the dotted lines in Fig. 1. To the inner side of the bracket L is pivoted transversely a plate, L' , (see Fig. 5,) at z , having an ear like the ears o on the block E , containing also a screw-pin, o' , provided with a wing-nut, o^2 , and upon the plate L' is a box, G^2 , in form like the boxes G and G' , and containing the screws H H' , jam-nuts k k' , extension m , and slotted extension l , as in the said boxes G G' , and pivoted 50 at its extension m to the plate L' , whereby an end of the roller K^3 may be adjusted by the screw H , and the pressure of the roller against the cylinder D and vibrator C may be varied by properly swinging the box G^2 and holding 55 it in position by tightening the wing-nut. 60

When thus adjusted and tightened, obviously tilting downward of the plate L' upon its pivotal bearing will raise the roller K^3 out of contact with the cylinder D and vibrator C , and this is effected simultaneously with the removal of the rollers K , K' , and K^2 from such contact by means of the cam F by connecting the plate L' toward its rear extremity with the block E by a link, M , as shown. Thus whenever the rollers K , K' , and K^2 are lowered 70 from contact with the cylinder D and vibrator C the roller K^3 is raised from such contact, and when the first-named rollers are raised into such contact the roller K^3 is lowered to act upon the form-cylinder and vibrator. 75

It will be noticed that the box G is shown in Fig. 1 in dotted lines, the purpose being to avoid obstructing the flaring extension p and permit the ear o to be shown, which, as o' on the extension p' , is obstructed by the box G' . 80

What we claim as new, and desire to secure by Letters Patent, is—

1. The combination, with the form-cylinder of a printing press and the ink-drum, of ink-rollers supported in reciprocating bearings, and an ink-roller supported in pivotal bearings connected with the reciprocating bearings, whereby moving the said reciprocating bearings adjusts the ink-rollers supported 90 thereon with reference to the form-cylinder and ink-drum and simultaneously and similarly adjusts the said ink-roller supported in pivotal bearings, substantially as and for the purpose set forth. 95

2. The combination, with the form-cylinder of a printing-press and the ink-drum, of ink-rollers independently adjustable on pivotal bearings independently adjustable transversely to the rollers and simultaneously adjustable into and out of contact with the form-cylinder and ink-drum, substantially as and for the purpose set forth. 100

3. The combination, with the form-cylinder of a printing-press and the ink-drum, of frames 110 B and blocks n , secured upon the frame of the press, blocks E , dovetailed into the blocks n to reciprocate vertically, and carrying adjustable pivoted boxes G and G' and rigid central boxes, g , the boxes containing adjusting-screws 115 H , carrying bearings I , to receive the journals of ink-rollers, and adjustable pivoted boxes G^2 on the upper ends of the frames B , connected with the blocks E and containing adjustable screws H , carrying bearings I , to receive the journals of an ink-roller, K^3 , substantially as and for the purpose set forth. 120

4. The combination, with the form-cylinder of a printing-press and the ink-drum, of frames B and blocks n , secured upon the frame of the press, blocks E , dovetailed into the blocks n to reciprocate vertically, and carrying adjustable pivoted boxes G and G' and rigid central boxes, g , the boxes containing adjusting-screws H , carrying bearings to receive the journals 125 130

of ink-rollers, cams F, underneath the blocks E on a rock-shaft, F', plates L', pivotally secured upon the upper sides of the frames B, adjustable boxes G², pivoted to the plates L' and containing adjusting-screws H, carrying bearings I, to receive the journals of an ink-roller, K³, and a link, M, connecting the plates L' with the reciprocating blocks E, the whole being

constructed and arranged to operate substantially as and for the purpose set forth.

FREDERICK L. GOSS.
SAM G. GOSS.
